[57] CLAIM

The ornamental design for a hand held personal scanner, as shown and described.

DESCRIPTION

FIG. 1 is a perspective view of a hand held personal scanner showing my new design;

FIG. 2 is a top view thereof;

FIG. 3 is a front elevational view thereof;

FIG. 4 is a bottom view thereof;

FIG. 5 is a right side elevational view thereof;

FIG. 6 is a left side elevational view thereof; and,

FIG. 7 is a rear elevational view thereof.

The broken line showing of an attachable printer and tether in FIG. 1, the numerals and lettering in FIGS. 1, 3 and 6, and a tether attachment port in FIG. 5 is for illustrative purposes only and forms no part of the claimed design.

1 Claim, 2 Drawing Sheets
